UNITED STATES PATENT OFFICE.

FREDERICK T. BRADISH, OF BOSTON, MASSACHUSETTS, ASSIGNOR OF TWO THIRDS TO ALONZO G. BRADISH, OF MEDFORD, AND C. FRED FELLOWS OF MALDEN, MASSACHUSETTS.

FASTENING DEVICE FOR TUBS, BOXES, &c.

SPECIFICATION forming part of Letters Patent No. 605,470, dated June 14, 1898.

Application filed August 11, 1897. Serial No. 647,834. (No model.)

To all whom it may concern:

Be it known that I, FREDERICK T. BRADISH, of Boston, county of Suffolk, State of Massachusetts, have invented an Improvement in 5 Fastening Devices for Tubs, Boxes, &c., of which the following description, in connection with the accompanying drawings, is a specification, like letters on the drawings representing like parts.

10 This invention relates to staple-like devices employed in securing the covers or tops of wooden tubs, boxes, pails, and the like, and has for its object the improvement of the fastening device forming the subject-matter 15 of United States Patent No. 517,836, granted to me April 10, 1894. In the staple-like fastener therein shown the crown is provided with serrations or depressed portions constituting lines of weakness transverse to the 20 length of the fastener, so that when bent over the edge of a tub or box the fastener will bend squarely at one of such weakened portions.

The fasteners are in practice usually made from coppered or tinned wire, swaged or 25 shaped by suitable dies, and it has been found that the swaging to form the thin portions of the crown acted to greatly compress and harden the metal, making it so brittle that it had to be afterward annealed to restore its 30 softness and permit bending of the fastener without breaking. Such annealing destroyed the copper or tin coating of the fastener, and consequently the fasteners had to be recoppered or retinned after annealing. Both the 35 annealing and recoating operations materially increased the cost of manufacture; and this present invention has for its object the production of a staple-like fastener which can be readily bent without annealing and 40 recoating subsequent to the swaging. I accomplish this object by reducing the crown in thickness to enable it to be readily bent transversely, but a longitudinal strengthening-rib is extended along the crown, the action 45 of the forming-dies leaving the rib comparatively soft and flexible, so that when the fastener is bent the rib will not break or rupture. By such construction I retain all of the valuable features of my patented fastener 50 referred to, while entirely obviating two nec-

essary steps in its manufacture and greatly reducing its cost.

Figure 1 is an under side view, enlarged, of a fastener embodying this invention. Fig. 2 is a side elevation of the fastener shown in 55 Fig. 1. Fig. 3 is an enlarged transverse section thereof on the line $x-x$, Fig. 2. Fig. 4 is a detail showing one of the fasteners as it will appear when driven into a tub or box.

The driving-legs $a-a$, joined by the crown $6c$ or top bar b , the latter of sufficient length to adapt the fastener for the work for which it is designed, the auxiliary bends b^2 at each end of the crown, and the raised flattened tops b^3 of the bends, forming driving-faces, are and 65 may be substantially as shown in my patent referred to.

In the fasteners shown in Figs. 1 to 4, inclusive, the crown b is provided, preferably, for the greater part of its length with a series 70 of serrations or depressions b' of a depth and size depending upon the size of the fastener and the character of the articles to which it is to be applied, such depressions or serrations, however, being always of such depth 75 that they constitute cross-lines of weakness in the crown, so that the latter when bent in either direction will naturally follow one of such lines of weakness.

As the fasteners are preferably made of 80 round wire, the action of the dies spreads the crown laterally as it is decreased in thickness by the formation of the depressions or serrations b' , and the thinned metal is so compressed that it is hardened and made comparatively brittle at the lines of weakness.

To obviate annealing and still maintain the strength and integrity of the crown when bent, I leave a central longitudinal rib b^5 , dividing each serration or depression at the center into two portions, said rib or enlargement being so slightly compressed that its softness is not appreciably decreased. Accordingly when the crown is bent, as shown in Fig. 4, along one of its lines of weakness the portion of the soft rib crossing such weakened portion will readily bend without fracture or breakage. I thus produce a fastener the crown of which has transverse lines of weakness in hardened comparatively brittle metal 95 100

crossed by a longitudinal strengthening-rib of relatively soft and readily-bent metal having little tendency to fracture or breakage.

By serrating or forming the depressions on the under side of the crown the latter is more easily embedded in the wood when the fastener is applied, the raised portions b^4 between the serrations and the strengthening-rib b^5 when so embedded acting to prevent lateral displacement of the fastener or working of the cover with relation to the tub or box.

I may duplicate the strengthening-ribs, if desired, and the exact shape or construction of fastener is not limited to the shape or construction herein shown. So, too, the auxiliary bends at the ends of the crown may be omitted and the serrations or depressions may extend for a greater or less distance along the crown without departing from the spirit and scope of my invention.

Having fully described my invention, what I claim as new, and desire to secure by Letters Patent, is—

1. The herein-described staple-like fastener, comprising two driving-legs, a connecting integral crown provided with serrations or depressions to form transverse lines of

weakness and facilitate bending of the fastener, and a strengthening-rib extended longitudinally of and integral with the crown, 30 substantially as described.

2. The herein-described staple-like fastener comprising two driving-legs, and a connecting-crown provided with transverse indentations or depressions to form lines of 35 weakness, said crown also having an integral longitudinal strengthening-rib crossing the indentations or depressions, substantially as and for the purpose described.

3. A staple-like fastener having two driving-legs, and a connecting-crown, the main portion of which has transverse lines of weakness in hardened and comparatively brittle metal, an integral longitudinal strengthening-rib of relatively soft and readily-bent 45 metal crossing such lines of weakness, substantially as and for the purposes described.

In testimony whereof I have signed my name to this specification in the presence of two subscribing witnesses.

FREDERICK T. BRADISH.
